UNITED STATES PATENT OFFICE

OTTO NICODEMUS, OF FRANKFORT-ON-THE-MAIN-HOCHST, GERMANY, ASSIGNOR TO
I. G. FARBENINDUSTRIE AKTIENGESELLSCHAFT, OF FRANKFORT-ON-THE-MAIN,
GERMANY, A CORPORATION OF GERMANY

PROCESS FOR EXTRACTING ACETYLENE OF HIGH VALUE FROM GASES POOR IN
ACETYLENE

No Drawing. Application filed December 19, 1928, Serial No. 327,175, and in Germany December 27, 1927.

The present invention relates to a process for extracting gases containing a high percentage of acetylene from gases poor in acetylene.

5 I have found that acetylene can be extracted from gases poor in acetylene and obtained as a valuable high per cent gas by using acetonitrile as washing agent. The extraction of the gases by means of acetonitrile can be effected by any one of the usual methods of absorbing gases in liquids, it being, however, advantageous to cool the washing agent to low temperatures, preferably between about 0° C. and -20° C. in 10 order to avoid any loss of acetonitrile. The boiling out of the acetonitrile charged with the acetylene gas may also be operated by any of the known methods.

Since acetonitrile is a substance which can 20 be produced at a low price and possesses in a high degree the power of dissolving acetylene and is also indifferent toward the action of metals or catalysts, it is highly suitable for the purpose of extracting in an 25 economic way from gases which are poor in acetylene gases containing a high percentage of acetylene which may for instance be directly utilized in any of the known technically valuable contact processes.

For instance a gas containing 51.6 per cent of methane, 38.8 per cent of hydrogen and 7.1 per cent of acetylene, if it is washed in a trickling tower according to the counter-current principle with acetonitrile which 35 has been cooled to -10° C., yields a waste gas of the following composition: 1.5 per cent of C_2H_2 , 40.7 per cent of H_2 and 55.5 per cent of CH_4 ; hence 80 per cent of the 40 acetylene contained in the gas mixture has been extracted therefrom. By boiling out the acetylene from the acetonitrile charged therewith an acetylene gas mixture is obtained which contains 93.5 per cent of acetylene, no hydrogen and 2.1 per cent of methane and which can be used directly for all technical purposes. The losses of acetonitrile which arise during the extracting and drying process are very small, whilst 45 the vapors which may possibly be carried

along can easily be almost completely removed by means of an absorbing agent or by washing it out with water and thus be recovered.

I claim:

1. The process of extracting acetylene from gases poor in acetylene which comprises washing said gases with acetonitrile at a low temperature. 55
2. The process of extracting acetylene from gases poor in acetylene which comprises washing said gases with acetonitrile at a temperature between -20° C. and 0° C. 60
3. The process of extracting acetylene from gases poor in acetylene which comprises washing said gases with acetonitrile at a temperature of about -10° C. 65
4. The process of extracting acetylene from gases poor in acetylene which comprises washing said gases with acetonitrile at a low temperature and then boiling out the acetylene from the acetonitrile charged therewith. 70
5. The process of extracting acetylene from gases poor in acetylene which comprises washing said gases with acetonitrile at a temperature between -20° C. and 0° C. and then boiling out the acetylene from the acetonitrile charged therewith. 75
6. The process of extracting acetylene from gases poor in acetylene which comprises washing said gases with acetonitrile at a temperature of about -10° C. and then boiling out the acetylene from the acetonitrile charged therewith. 80

In testimony whereof I have hereunto set my hand.

OTTO NICODEMUS.
